PARTS BIN

Frank Springer-Miller, Stowe, Vt., assignor to Snyder & Black, New York, N. Y., a corporation of New York

Application May 20, 1954, Serial No. 30,577

Term of patent 7 years

(Cl. D80—1)

To all whom it may concern:

Be it known that I, Frank Springer-Miller, a citizen of the United States of America, a resident of Stowe, State of Vermont, have invented a new and ornamental Design for a Parts Bin, of which the following is a specification, reference being had to the accompanying drawing, forming a part thereof.

Figure 1 is a front perspective view of a parts bin showing my new design.

Figure 2 is a side perspective view thereof.

Figure 3 is a sectional view on the line 3—3 of Figure 1.

The dominant features of my design reside in the portions shown in full lines.

I claim:

The ornamental design for a parts bin, as shown and described.
